(57) **CLAIM**

We claim the ornamental design for a J channel, as shown and described.

DESCRIPTION

FIG. 1 is an isometric front, top and left side view of the J channel showing our design.

FIG. 2 is an elevation side view thereof.

FIG. 3 is an elevation back view thereof.

FIG. 4 is a bottom view thereof.

FIG. 5 is an elevation front view thereof; and,

FIG. 6 is a top view thereof.
